EXPOSURE METER INSTRUMENT

Clement F. Taylor, Peabody, Clyde W. McCarty,
Swampscott, and Allen G. Stimson, Lynnfield,
Mass., assignors to General Electric Company,
a corporation of New York

Application August 26, 1947, Serial No. 770,668

5 Claims. (CL 171—95)

1

Our invention relates primarily to an electrical measuring instrument intended for use in a small sized exposure meter, and concerns features of construction and operation which permit of obtaining the required sensitivity when energized from a small light cell and the necessary compactness and ruggedness of construction for the purpose mentioned. Such features as are novel are not necessarily restricted for use in an exposure or light meter.

In carrying our invention into effect, we employ a permanent magnet field instrument with the permanent magnet inside the moving armature coil, and an external U-shaped magnetic return strap instead of the more conventional reverse arrangement. This enables us to obtain the necessary small diameter instrument for our purposes having the necessary high sensitivity. The magnetic circuit air gap is shaped to obtain a logarithmic open scale distribution desirable in exposure meters. We employ internal pivots and lead-in spiral return springs inside the armature coil instead of the more conventional arrangement where the lead-in spirals are outside the armature coil. This enables us to obtain the required length of coil without increasing the axial length of the complete instrument beyond the length of the armature coil. The instrument pointer is likewise secured to the armature inside the coil and swings in an arc the plane of which cuts the armature coil. Hence the maximum axial length of the instrument is the length of the armature coil which is made no longer than is necessary to obtain the required sensitivity in a well designed instrument. The internal permanent magnet is secured in fixed relation to the external flux return strap by a U-shaped strap which also acts as a spring and is used for adjusting the clearance between the jewels and internal pivots of the armature. The construction while small in size and high in sensitivity is nevertheless sufficiently rugged as to permit of the rough handling incident to being carried around in a person's pocket without getting out of calibrated adjustment.

The features of our invention which are believed to be novel and patentable will be pointed out in the claims appended hereto. For a better understanding of our invention reference is made in the following description to the accompanying drawing in which Fig. 1 represents an enlarged face view of an exposure meter, with the front cover of the casing removed and containing an instrument embodying our invention. Fig. 2 is a cross-sectional view through such an exposure

2

meter and instrument taken on line 2—2 of Fig. 1, and Fig. 3 is a perspective view of the magnetic circuit and armature coil assembly with the two axially separated for the sake of clarity of illustration.

The permanent magnet field for the instrument is supplied by a generally oblong-shaped salient pole permanent magnet 1 which is placed inside the armature and polarized across its long or major axis as indicated by the N and S designations in Figs. 1 and 3. The main pole piece sections which are part of the permanent magnet have an axial length somewhat longer than the central portion of the magnet. The permanent magnet 10 pole pieces are not exactly symmetrical; thus the N pole piece has a main elongated portion 2 and a shorter upscale extending portion 3. The permanent magnet shape is designed in relation to the outer flux return U-shaped magnetic part 4 to obtain the desired flux distribution. The U-shaped outer magnetic part 4 is secured in fixed relation to the internal permanent magnet 1 by a U-shaped nonmagnetic strap 5 which may be made of brass. The base part of the U-shaped 25 part 5 is welded to the inner central part of magnetic return part 4, and its lower limb is secured to the lower central portion of permanent magnet 1 by a rivet 6 (see Fig. 2) which extends upwardly through an axial hole in the permanent magnet 1 and is peened over at the upper surface at 7, thus 30 rigidly securing the lower limb of strap 5 to the magnet and to the flux return strap 5.

The upper limb of strap 5 is free of the magnet and supports the upper jewel 8, while the lower jewel 9 is supported in the lower end of rivet 6. A screw 10 extends through a hole in the upper limb of strap 5 and is threaded into the lower limb thereof at a point between magnet 1 and magnetic return part 4. The two limbs of 5 are originally 40 bent to have a tendency to spread apart a greater distance than the required distance between the pivots 8 and 9, and this spreading is restricted and is adjustable by the screw 10 which thus serves as the jewel spacing adjustment. Preferably, the upper limb of the part 5 is weakened as by an opening at 11 near part 4, so that the bending caused by adjustment of screw 5 comes at point 11, and hence the pivot adjustment is substantially in an axial direction, and proper axial alignment of the jewels is obtained when the adjustment is correct. It is to be noted that the strap 5 embraces the magnet 1 at the reduced axial length central portion thereof, and that the upper surface of the permanent magnet has an 50 additional recess at 12 to accommodate the upper

limb of 5, so that a desired restricted axial spacing of the jewels 8 and 9 is obtained. Owing to the oblong shape of the permanent magnet this recess at its center portion does not reduce its cross-sectional area to the point where it would be of an inefficient design.

The armature coil 14 with its internal pivots 15 and 16 is rotatively supported in the jewels 8 and 9, with the coil sides movable in the air gap between the inner permanent magnet 1 and outer flux return member 4, as represented in Figs. 1 and 2. The lower lead-in spiral 17 is fastened at its inner end to the inner side of the coil at the button which supports lower pivot 16. The outer end of this spiral 17 is secured to an arm 18 which has a hub portion pivoted about rivet 6 between the lower limb of strap 5 and a collar on the rivet. Arm 18 is engaged by a forked lever 19 secured to and rotatable with a zero set pin 20 rotatively mounted through the bottom wall portion 21 of the casing employed. The pin 20 is friction tight but may be rotated with a screw driver from outside the casing to adjust the tension of lower spiral 17 and thus the zero position of the armature pointer 22 on the instrument scale 23. The inner end of the upper spiral 24 is secured to the inner side of coil 14 at the button which supports the upper pivot 15, and the outer end of the spiral is secured by a strap 25 fixed to the casing structure as by molding. It is thus seen that the jewels, pivots, and lead-in spirals of the armature assembly are inside the length of the coil, and that the total axial length of the instrument corresponds to the total length of the coil.

The casing may be made out of some molded insulating compound such as plastic, hard rubber, etc. As represented, it is made in two sections, a cover section 30 and the base section 21. These sections are fitted together at a joint 31 and after assembly of the instrument in the casing. These sections may be secured together by screws or cement.

The casing contains a light cell at 32 which may be exposed to light through a transparent window glass 33 and corresponding upper end opening in the casing. The window glass is held in place against the inside wall of the casing over the window opening by a resilient wire spring part 34 inserted between the glass 33 and a ledge 35 molded into the casing structure. An analogous arrangement secures the cell 32 in place. The light cell 32 is electrically connected across the armature coil 14 through the spirals 17 and 24, so that when the cell is exposed to light through window glass 33, current flows in coil 14 to cause the instrument to deflect upscale in proportion to the light value. The electrical connections are not completely shown.

To the front of the light cell and window therefor is the scale plate 36 having the scale 23 on its front surface, and over which the instrument pointer 22 is adapted to swing. The scale and pointer are exposed to view through a front glass window at 37 and corresponding opening to the front cover section 30 of the casing. The inner wall of the casing is molded to accommodate the parts contained therein and, in particular, to fit snugly about the outer limb portions of the magnetic return strap 4 of the instrument. This strap 4 has rearwardly extending anchor projections 38 at its ends which fit tightly into corresponding recesses molded into the base section of the casing. The strap 4 preferably is sprung inwardly very slightly in inserting it into place,

so that it is securely fastened into the casing when pushed downward into place. The strap 4 with the instrument assembled thereon is inserted prior to assembling the scale plate 36, and the scale plate is then secured in place by large headed screws 39. The scale plate fits against the upper edge of the yoke portion of strap 4, and no additional fastening means is required for securing the instrument firmly in the casing. The downscale instrument deflection is limited by a stop member 40 of insulating material against which the coil 14 rests in the zero indicating position.

It is to be noted from the shape and dimensions of the magnetic parts forming the air gap that as the armature turns in a upscale direction from the zero indicating position, it first moves into an abruptly increasing strength of field flux across the air gap to about 15 degrees from the zero end and then into a much more gradually decreasing strength of field flux crossing the air gap. The point of maximum field strength is in part obtained by the elongations of the pole pieces of the permanent magnet on both ends thereof, and in part by the reduced air gap at this point. The gradually diminishing air gap field strength is largely obtained by the offset but reduced length portion 3 of the salient pole internal permanent magnet and the gradual increase in air gap opposite thereto over the remaining range of deflection of the instrument. The total angle of deflection provided for is approximately 55 degrees. The arrangement provides for and produces an open, uniformly graduated logarithmic scale as shown. It is to be noted that the offset portion 3 of the permanent magnet occurs at only one salient pole and not the other. The outer flux return strap 4 is of U shape and does not extend completely around the air gap, and there is little leakage flux in the air gap area where the strip U is absent.

A successful instrument of this character has been built having an armature coil approximately three-fourths of an inch in diameter, with the other proportions as illustrated. Thus the diameter of the armature coil is substantially greater than its axial length. In order to obtain the necessary flux strength and sensitivity using an internal permanent magnet of the small size required, it is necessary that the permanent magnet be made of a high-grade permanent magnet material, such as the material described in United States Patent No. 2,295,082, September 8, 1942, to Jonas. Placing the lead-in spirals, which also serve as zero return springs, inside the armature instead of outside, permits of the reduced axial length of the armature illustrated, and at the same time allows for a satisfactory axial spacing between the internal pivots. If these pivots are placed too close together, the rotary system lacks stability and pointer flop results.

The complete instrument and casing as built has a depth of $\frac{5}{8}$ inch, a width of $1\frac{1}{2}$ inches, and a length of $1\frac{1}{2}$ inches, maximum dimensions. This small size is obtained with a logarithmic scale instrument which is both rugged in construction and of the required sensitivity, having the structural features described.

What we claim as new and desire to secure by Letters Patent of the United States is:

1. An electrical measuring instrument comprising an internal oblong-shaped permanent magnet having integral salient pole pieces of op-

posite magnetic polarity at the extremities of its major axis, an external U-shaped magnetic return strap for said permanent magnet with its limbs spaced from and opposite the pole pieces of said magnet to provide an armature air gap having its minimum length and maximum flux density areas opposite said pole pieces, nonmagnetic means secured between the central portions of said magnet and return strap for securing said parts in fixed relation, an armature coil pivoted centrally of said magnet with its coil sides in said air gap, said coil having a range of rotation from below to above the concentrated flux areas of said air gap, one of the pole pieces of said magnet having an unsymmetrical extension in the upscale direction of rotation of said coil to provide an air gap area of gradually diminishing flux strength for the coil as it rotates upscale from the concentrated flux air gap areas.

2. An electrical measuring instrument comprising an internal permanent magnet of oblong shape with integral pole pieces of opposite magnetic polarity at the extremities of its major axis, an external U-shaped strap of magnetic material with its limbs spaced from the pole pieces of the magnet to provide a flux return path therefor, a U-shaped strap of nonmagnetic material secured at its base to the inner side of the base of the U-shaped magnetic return strap and straddling the central portion of the permanent magnet, with one limb of said nonmagnetic part secured to said magnet and the other limb free, an armature coil having an axis of rotation centrally of said magnet and passing through the limbs of said nonmagnetic strap and with its coil sides in the air gap between the permanent magnet and flux return strap, internal jewels for said coil on opposite sides of said permanent magnet, one of which is secured in fixed relation to said magnet and the other of which is carried by the free limb of the nonmagnetic strap, and means for adjusting the spacing between the limbs of said nonmagnetic strap to adjust the spacing between said jewels.

3. An electrical measuring instrument having internal and external magnetic parts separated by an air gap, one of said parts comprising a permanent magnet for producing a flux across said gap and the other part providing a flux return path for the permanent magnet, an armature coil pivoted centrally of the internal part with its coil sides rotatable in said air gap, a U-shaped strap of nonmagnetic material secured at its base to the external magnetic part and with its limbs straddling the internal magnetic part on the axis of rotation of said coil, one limb being secured to said internal magnetic part and the other limb being free, internal jewels for pivoting said coil at opposite ends of said internal part one jewel being secured to said internal part and the other being secured in the free limb of said nonmagnetic part, said free limb being made flexible near the point where secured to

said external part for the purpose of adjusting the spacing between said jewels, and a screw extending between said limbs for adjusting such spacing.

- 5 4. An electrical measuring instrument comprising an internal permanent magnet of oblong shape and having integral salient pole pieces of opposite magnetic polarity at the extremities of its major axis, an external U-shaped magnetic strap forming a magnetic return path for the flux of said magnet, the limbs of the strap being spaced from the poles of the magnet to form an armature air gap, an armature coil pivoted to rotate in said gap, a central opening in the permanent magnet on the axis of rotation of said coil, a U-shaped member of nonmagnetic material secured at its base to the base of said magnetic return strap and with its limbs straddling the permanent magnet within and on the axis of rotation of said coil, a rivet extending through the opening in said permanent magnet and one of the limbs of said nonmagnetic member for securing the permanent magnet and magnetic strap in fixed relation, internal pivot jewels for said coil, one of which is located in the end of said rivet and the other of which is carried by the other limb of said nonmagnetic member, and means for adjustably flexing the last-mentioned limb to adjust the spacing between said jewels.
- 10 5. An electrical measuring instrument comprising an internal permanent magnet and an external magnetic return core, said parts being separated by an armature air gap, an armature coil surrounding the permanent magnet and pivoted on an axis passing therethrough, said coil having a diameter which is greater than its axial length, internal pivots for said armature, lead-in spirals for said armature within the coil, and a pointer for said instrument secured to the
- 15 40 armature coil and rotating in a plane extending through said coil, said instrument parts as assembled having an axial length no greater than the length of the armature coil.
